UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,943, dated June 24, 1890.

Application filed April 16, 1890. Serial No. 348,101. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

10 In the drawing is shown a side elevation of a cane or umbrella handle illustrating my new design.

15 A is the lower portion of the body, and is formed of two upwardly and laterally extending or spreading leaves D D of plain surface and terminating in the spirals E E. The body part A is finished at the lower portion of the base-band F of plain surface. This body part A extends laterally in one direction to form a crook B and in the other direction to form the upwardly-extending heel C. The crook B terminates in a form of hoof

H of plain surface, and is covered by a series of curved ribs G, highly relieved and plain. The heel C curves upward, terminating in 25 the point J, and the downwardly-extending ribs I and K extend over said heel upon its faces, substantially as shown. The portion of the body above the parts D and uncovered by the parts G I K is shaded to give 30 high relief to the plain portions.

The handle is made of any suitable material.

Having now described my new design, what I claim as new, and desire to secure by Letters Patent, is—

The design for cane or umbrella handles, substantially as described and shown.

In testimony of which invention I have hereunto set my hand.

HENRY O. SCHMIDT.
